CLAIM

The ornamental design for pet steps, as shown and described.

DESCRIPTION

FIG. 1 is a perspective view of pet steps showing my new design;

FIG. 2 is a front elevation view thereof, the rear elevation view being a mirror image;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is another perspective view thereof, in a folded position.

(Continued)

The broken lines depict exemplary features for illustrative purposes only and form no part of the design claim.

1 Claim, 7 Drawing Sheets
